HAIR WAVING CLAMP

Bernard A. Sterling, Chicago, Ill.

Application April 15, 1935, Serial No. 16,314

6 Claims. (Cl. 132—36.1)

This invention relates to a hair-waving or protector clamp for application to the hair during the process of waving the same, and may be characterized as an improvement upon the hair waving clamp disclosed and claimed in my copending application, Serial No. 748,992, filed October 19, 1934.

One of the features of the present invention is the provision of improved resilient facing members for the jaws of the clamp, and particularly an improved spring arrangement for the meeting surfaces of these members whereby to improve the action and increase the life of these surfaces, particularly along the location where the bunched strand of hair is gripped.

Another feature is the provision of an improved mounting for these resilient facing members, which mounting will permit convenient removal and reversal of the facing members on the jaws of the clamp.

Another feature resides in an improved mounting and stop arrangement for the spring pawl for holding the hair-waving spool against unwinding.

Further features and the advantages of the invention will be apparent from the following detailed description, taken in connection with the accompanying drawing, in which:

Figure 1 is a side elevational view of a hair-waving clamp embodying the present invention, showing the waving spool applied thereto;

Figure 2 is a top plan view, partially broken away and in section, showing the jaws in open position and a bunch of hair positioned therebetween;

Figure 3 is a fragmentary top plan view, partially in section, with the jaws in closed position;

Figure 4 is a detail section taken on the line 4—4 of Figure 2; and

Figure 5 is a detail section taken on the line 5—5 of Figure 2.

Referring to the drawing, the clamp selected for illustration comprises a pair of elongated jaws 5 and 6 pivotally connected together at one end at 7 and provided, at the opposite end, with a device for closing the jaws and locking the same in closed position. This device is similar to the jaw closing and locking device disclosed and claimed in my copending application, Serial No. 748,992, filed October 19, 1934.

In the illustrated embodiment, each jaw 5 and 6 is in the form of a sheet metal stamping of channel section. At its pivoted end, the channel section of the jaw 5 has its top and bottom flanges extended to form projecting tongues 8 which receive, between them, a pair of integral

tongues 9 offset to lie closely together and extending out laterally from the top and bottom flanges of the jaw 6. The tongues 8 and 9 are pivotally joined by the pivot 7, which may be in the form of a rivet or of other suitable or preferred form. The pivoted end of the jaw 6 has a tab 11 which is widened and turned up and notched at 12 to receive and support rotatably the adjacent end of the curler spool, indicated in its entirety at 13.

The back of the jaw 5 terminates short of the free end of the jaw, leaving the projecting tongues 14. The upper tongue 14 is elongated and folded back and turned up at 15 to form one side of the journal for the adjacent end of the curler 13. The back of the jaw 6 likewise terminates short of the free end of the jaw, and the adjacent end of the top flange of the channel section of this jaw is widened, turned up at 16, and notched at 17 to receive and support rotatably the adjacent end of the curler 13, the upturned journal part 15 on the jaw 5 constituting the other part of this journal, and when the jaws 5 and 6 are closed, holding the adjacent end of the curler 13 against lateral displacement from the journal part 16.

Short of its free end, the bottom flange of the channel section of the jaw 5 has an integral lug 18 (Figure 4) turned up and abutting the top flange of the jaw 5 to hold the top and bottom flanges of this jaw in proper spaced relation. Similarly, the bottom flange of the jaw 6 is provided short of its free end with an integral lug 19 turned up and abutting the top flange of this jaw (Figure 5) to hold these flanges in proper spaced relation.

The facing members 20 are formed of resilient material, such as relatively live or yielding rubber or the like, and are of channel-shaped section to embrace and snugly grip the jaws 5 and 6 as shown. When the facing members are in position upon the jaws 5 and 6, the bottoms of these facing members lie along the under sides of the bottom flanges of the respective jaws 5 and 6, and the upstanding side flanges 21 and 22 lie along the backs and along the open inner sides respectively of the jaws 5 and 6. Integral flanges 23, turned inwardly from the upper ends of the side flanges 21 and 22, engage the upper sides of the jaws 5 and 6 and hold the facing members in place upon the respective jaw members. The channel section and yielding character of the members 20 permit convenient removal and reversal of these facing members on the jaws of the clamp. Thus either flange 21 or 22 of either facing member may be disposed along the inner

sides of the jaws 5 and 6 for gripping cooperation with the hair, and after such use of one flange, the facing member may be removed and reversed to present the other flange along the inner side 5 of the jaw. The outer surfaces of the flanges 21 and 22 of each facing member may be ribbed or grooved as shown in Figure 1.

A heat insulating strip 25, of felt or other suitable material, is secured to the bottom of each 10 of the facing members 20 preferably by means of parallel lines of stitching indicated at 26. Of course these strips 25 may be secured to the members 20 in any other suitable or preferred manner. The strips 25 are substantially coextensive with the facing members 20, and their 15 opposite ends project endwise beyond the members 20 to underlie substantially the entire length of each jaw 5 and 6. The relatively flat form of the channel-shaped jaws 5, together with the 20 rounding of the upper and lower edges of the backs of these jaws, permit the facing members to be applied and removed sidewise and then turned to the position shown, although the form and yieldability of the members 20 will permit 25 these members to be applied from the bottom and directly to the desired position and similarly removed.

Disposed within the channel sections of the jaws 5 and 6 are springs 28 having intermediate 30 portions 29 lying along the open inner sides of the jaws. The inturned ends 30 of the springs 29 terminate in longitudinal extensions which are adapted to be sprung between and into interlocking engagement with prongs 32 pressed in from 35 the back walls of the jaws 5 and 6. The springing of the ends of the springs 28 between and into engagement with the prongs 32 secures the springs 28 removably in position within the jaws and bows the intermediate portions 29 outwardly 40 and places the same under tension. These bowed intermediate portions 29 of the springs 28 press the inner side flanges of the facing members 20 inwardly and provide an effective gripping action upon the bunched strand of hair placed between 45 the jaws, as indicated at 34. The springs 28 maintain an effective gripping action of the members 20 upon the hair at all times and increase the life of the members 20, particularly 50 along the locations where the hair is gripped. And the life of these members 20 is further increased by the reversibility of the same upon the jaws 5 and 6. The springs 28 preferably bow the inner sides of the facing members 20 to convex form along the locations where the hair 55 is gripped, as shown at 35 in Figure 2.

The particular curler 13, selected for illustration, is of the type more fully disclosed in my prior patent, No. 1,862,721, patented June 14, 1932. Suffice it to say that this curler comprises the 60 metal spool or reel 36 of circular section, diminishing in diameter from its opposite ends toward the center, and a saddle-like retainer 37 pivoted to one end of the spool at 38. A finger-piece 39 is provided at one end of the spool for 65 turning the same, and the opposite end of the spool has teeth 40 which cooperate with a spring pawl 42 to prevent unwinding of the spool.

The spring pawl 42 comprises a spring strip 70 turned in beneath the bottom of the jaw 6 and secured thereto as by means of a rivet 43. A prong 44, struck in from the spring strip, engages the teeth 40 and holds the spool against unwinding. The upper end of the spring strip is rounded or turned at 45 to be actuated by the 75 operator's finger for the purpose of releasing the

prong 44 from the teeth 40. A small lug 46, integral with the journal part 16, forms a stop for limiting the releasing action of the spring pawl.

The device for closing the jaws and locking the 5 same in closed position comprises a lever 50 pivoted for free swinging movement at one end at 51 between the tongues 14 of the jaw 5. The lever 50 comprises a pair of superposed arched pieces between the pivoted ends of which a washer 10 52 is provided. A latch 53 is pivoted at 56 between the free ends of the arched pieces constituting the lever 50, and this latch 53 preferably has a shoulder 54 which, by engagement with an integral stop 55 turned down from the edge of 15 the top piece of the lever 50, limits swinging movement of the latch in a clockwise direction with respect to the lever 50 as viewed in Figure 2. The pieces constituting the lever 50 have lips 50' turned in, or the pieces are otherwise formed to 20 bear against the latch member 53 to prevent free turning of the latch with respect to the lever. As a result, the latch 53 and lever 50 swing substantially as a unit about the pivotal connection at 51 with the jaw 5, and until the latch 25 engages the other jaw, whereupon the latch and lever swing about their respective pivots, as will appear. The latch 53 has a relatively short projecting finger 57 provided with a rounded cam edge 58 which has a depression 59. The latch 30 53 also has a finger-piece 60 turned at substantially right angles to the pivoted part of the latch and preferably elongated to give the operator a considerable mechanical advantage in closing and locking the device. 35

Further, to facilitate ease of operation of the device, the part on the jaw 6 for cooperation with the jaw closing and locking latch 53 is in the form of a roller 62. This roller 62 is mounted between integral tongues 63 projecting endwise from the 40 top and bottom flanges of the channel section of the jaw 6 for free turning movement upon a pin 64 fixed in the tongue 63 as by heading one end and riveting over the opposite end of the 45 pin.

With a bunch of hair between the jaws 5 and 6 as shown in Figure 2, the device is closed by applying the finger to the finger-piece 60 and pressing the same in the direction indicated by the arrow in Figure 2. This swings the latch 53 and 50 lever 50 as a unit, or at least substantially as a unit, about the pivot 51 until the finger 57 takes over the roller 62. Thereupon, as the finger-piece 60 is pressed further in the same direction, the lever 50 continues its swinging movement in 55 a counter-clockwise direction about the pivot 51 and, at the same time, the latch 53 swings in a counter-clockwise direction about the pivot 56. The resulting action gives the operator great mechanical advantage and forces the jaws 5 and 60 6 positively to closed position with great force. The roller action, due to the engagement of the roller 62 with the latch 53, further facilitates the closing and locking action, and as the pin 64 moves into or past dead center *a—a* (Figure 3), 65 the jaws 5 and 6 are locked positively in closed position.

I do not intend to be limited to the precise details shown or described.

I claim:

1. In a hair waving clamp, a generally channel-shaped jaw member having a back portion and an open side, a resilient facing member secured to said jaw member and having a hair gripping portion covering the open side of said 75

jaw member, prongs on the inner side of the back portion of said jaw member, and a spring having lugs at its opposite ends adapted to be sprung between and into interlocking engagement with said prongs to hold the spring to said jaw member independently of said resilient facing member, said spring being disposed within said channel-shaped jaw member and confined between the back portion of said jaw member and the hair gripping portion of said facing member for pressing the hair gripping portion of said facing member yieldingly into engagement with the hair when the clamp is applied thereto.

2. In a hair waving clamp, a generally channel-shaped jaw member having a back portion and an open side, a resilient facing member secured to said jaw member and having a hair gripping portion covering the open side of said jaw member, prongs on the inner side of the back portion of said jaw member, and a spring having lugs at its opposite ends adapted to be sprung between and into interlocking engagement with said prongs to hold the spring to said jaw member independently of said resilient facing member, said spring being disposed within said channel-shaped jaw member and confined between the back portion of said jaw member and the hair gripping portion of said facing member for pressing the hair gripping portion of said facing member yieldingly into engagement with the hair when the clamp is applied thereto, said spring being adapted to have continuous engagement with said facing member and free except for engagement with the facing member throughout its entire extent between the engagement of the lugs on the opposite ends of the spring with the prongs on the back portion of said jaw member.

3. In a hair waving clamp, a jaw member, a resilient facing member carried by said jaw member for gripping engagement with the hair, a spring member adapted for uninterrupted engagement with said facing member throughout substantially its entire length for pressing said facing member yieldingly into engagement with the hair when the clamp is applied thereto, and means securing the opposite ends of said spring to said jaw member and holding the spring in

place to said jaw member independently of said resilient facing member.

4. In a hair waving clamp, a jaw member, a resilient facing member carried by said jaw member for gripping engagement with the hair, a spring member adapted for uninterrupted engagement with said facing member throughout substantially its entire length for pressing said facing member yieldingly into engagement with the hair when the clamp is applied thereto, and means securing the opposite ends of said spring to said jaw member and holding the spring in place to said jaw independently of said resilient facing member, said last means comprising prongs on said jaw member and cooperating lugs on the ends of said spring member.

5. In a hair waving clamp, a generally channel-shaped jaw member having a back portion and an open side, a resilient channel-shaped facing member fitting externally over said jaw member at the open side thereof and completely covering the open side of said jaw member, prongs on the back of said jaw member, and a spring having lugs at its opposite ends adapted to be sprung into engagement with the prongs on the back of said jaw member and held within said jaw member entirely independently of said resilient facing member.

6. In a hair waving clamp, a generally channel-shaped jaw member having a back portion and an open side, a resilient channel-shaped facing member fitting externally over said jaw member at the open side thereof and completely covering the open side of said jaw member, prongs on the back of said jaw member, and a spring having lugs at its opposite ends adapted to be sprung into engagement with the prongs on the back of said jaw member and held within said jaw member entirely independently of said resilient facing member, said spring having a single bowed portion extending through substantially the entire distance between the lugs at the ends of the spring and adapted for uninterrupted engagement with said resilient facing member throughout substantially the entire length of said spring.

BERNARD A. STERLING.
